UNITED STATES PATENT OFFICE.

JOSEPH SURY, OF WYNEGHEM, AND EDMOND BASTYNS, OF ANTWERP, BELGIUM,
ASSIGNORS TO SOCIÉTÉ ANONYME "LA PHOTOGRAPHIE DES COULEURS," OF ANT-
WERP, BELGIUM.

PROCESS OF TREATING PHOTOGRAPHIC PAPER.

1,010,200.

Specification of Letters Patent. Patented Nov. 28, 1911.

No Drawing.

Application filed March 11, 1909. Serial No. 482,791.

To all whom it may concern:

Be it known that we, JOSEPH SURY, a subject of the King of Belgium, residing at Wyneghem, Belgium, engineer chemist, and 5 EDMOND BASTYNS, a subject of the King of Belgium, residing at 29 Rue des Tanneurs, Antwerp, Belgium, druggist, have invented certain new and useful Improvements in Processes of Treating Photographic Paper, 10 of which the following is a specification.

This invention relates to the printing on paper of photographs in colors using three negatives obtained by the "three-color" process, the paper being the only and final 15 "basis" and the process used, three successive printings after a suitable sensitizing of the paper. Generally the printing of photographs in colors is obtained by superposing three separately printed phototypes (either 20 two positive plates with a film, bearing the third image interposed, or three carbon prints transferred one on the other).

In this invention an ordinary paper (preferably a paper, retaining its initial size notwithstanding repeated wetting and drying) 25 is coated with a sensitizing solution giving a blue print (for instance ferro-prussiate solution) on which the plate taken with the red screen is printed. After washing and 30 drying a second sensitizing is proceeded with but this time with a solution giving a yellow print (for instance bichromated gum in which a suitable yellow color has been mixed). The plate taken with the green 35 screen is next printed, the print being subsequently washed and dried. The picture is green at the places where the blue printing and the yellow are superposed. A third sensitizing with a suitable red solution (for 40 instance bichromated gum in which a suitable red pigment has been mixed) is followed by the printing of the plate taken with the blue-violet screen. This last printing gives all the intermediate tints between 45 red and violet according to the presence more or less marked of each of the three fundamental colors. The three successive prints are thus made one on the top of the other by superposition.

50 The inventors are aware that in certain bichromated gum processes several successive printings are sometimes used but the means

employed as well as the result are quite different. In the bichromated gum process a monochrome print is intensified, one negative being employed, while in the present case three prints each of a different color are printed successively one on the top of the other by superposition from three corresponding negatives with the result that a 60 polychrome picture is obtained.

Any kind of printing giving monochrome pictures of a particular color can be used and the order of superposing them is indifferent.

Regarding the paper it was found that after the ferro-prussiate printing was done the drying of the bichromated gum coating resulted in a shrinking of the paper and consequently the two pictures did not "register," that is to say the corresponding points of two negatives did not coincide in the printing. In order to avoid this shrinkage, the paper is first put in a solution of formic aldehyde or a tanning solution. 75 After drying, the back of the paper is coated with a solution of gum or sugar in water (gum, dextrin, sugar, glucose or other similar product). This has the effect of making the paper shrink before the ferro-prussiate printing is done, to the same extent as it will shrink when drying after the coating with the yellow or red gum solution. The three negatives will therefore "register" exactly. This permits of the paper 85 being sold ready for the blue printing.

What we claim as our invention and desire to secure by Letters Patent is:—

1. A process of treating photographic paper for the purpose of preventing the shrinkage thereof during printing consisting in treating the paper with a tannin solution, drying the treated paper and then treating the paper with a gum solution.

2. A process of treating photographic paper for the purpose of preventing the shrinkage thereof during printing consisting in treating the paper with a tannin solution such as formic aldehyde, drying the treated paper and then treating the paper 100 with a gum solution.

3. A process of treating photographic paper for preventing the shrinkage thereof consisting in treating the paper with a tan-

nin solution, drying the treated paper and coating the back of the paper with a gum solution.

4. A process of treating photographic paper for preventing the shrinkage thereof consisting in treating the paper with a tannin solution, such as formic aldehyde, drying the treated paper, and coating the back of the paper with a gum solution.

In testimony whereof we have hereunto signed our names to this specification in the presence of two subscribing witnesses.

JOSEPH SURY.
EDMOND BASTYNS.
